UNITED STATES PATENT OFFICE

171,911

SPOON OR SIMILAR OTHER ARTICLE OF FLATWARE

Louis P. Reizenstein, Pittsburgh, Pa.

Application August 3, 1953, Serial No. 26,230

Term of patent 3½ years

(Cl. D54—12)

To all whom it may concern:

Be it known that I, Louis P. Reizenstein, a citizen of the United States of America, residing at Pittsburgh, Pennsylvania, have invented a new, original, and ornamental Design for a Spoon or Similar Other Article of Flatware, of which the following is a specification, reference being had to the accompanying drawing, forming a part hereof.

Fig. 1 is a front elevational view of a spoon embodying my new design.

Fig. 2 is a sectional view thereof taken on the line 2—2 of Fig. 1.

Fig. 3 is a sectional view taken on the line 3—3 of Fig. 1.

Fig. 4 is a side elevational view of the spoon of Fig. 1.

The back of the spoon is plain, and the dominant feature of the design is shown in full lines.

I claim:

The ornamental design for a spoon or similar other article of flatware, as shown and described.
